UNITED STATES PATENT OFFICE.

ERNEST GROSSENBACHER, OF FAJARDO, PORTO RICO.

AUTOMATIC REGULATOR FOR FUEL-OIL BURNERS.

Application filed March 15, 1922. Serial No. 543,849.

To all whom it may concern:

Be it known that I, ERNEST GROSSEN-
BACHER, a citizen of the United States of
America, and a resident of Fajardo, Porto
Rico, have invented certain new and useful
Improvements in Automatic Regulators for
Fuel-Oil Burners, of which the following is
a specification.

My invention relates to automatic regu-
lators for fuel oil burners, and more partic-
ularly to that type which includes an oil
valve connected with an oil pipe leading
from a fuel oil pump to the burner and a
steam valve connected with the steam line
leading from the boiler in which steam is
being generated. In such installations, it is
evident that if the oil pressure remains con-
stant and the steam pressure varies, no
constant proportions in the mixture of oil
and steam can be automatically maintained
if the valve openings through which the
mediums pass increase and decrease to the
same extent. As it is essential to the main-
tenance of a clear flame, whereby the most
efficient heating results and the most eco-
nomical consumption of oil are obtained,
and because boilers equipped with sensitive
and efficient burners generally operate un-
der greatly varying loads, it has accordingly
heretofore been necessary to constantly ad-
just the oil and steam valves relatively to
each other. The object of this invention is
to overcome this disadvantage and to pro-
vide a regulator whereby the proper propor-
tions of steam and oil in the mixture will be
automatically maintained regardless of any
variations in the steam pressure and where-
by the flame produced by the mixture will
be automatically regulated in accordance
with the requirements for most efficient and
economical operation. My invention will be
fully described hereinafter and the features
of novelty will be pointed out in the append-
ed claims.

In the accompanying drawings, which
illustrate examples of the invention without
defining its limits, Figure 1 is a sectional
elevation; Fig. 2 is a side elevation partly in
section; Fig. 3 is a plan view partly in sec-
tion, with parts omitted for the sake of
clearness; Fig. 4 is a detail view showing
the valve openings; Figs. 5 and 6 are dia-
grammatic views illustrating the operation
of the invention; Fig. 7 is a sectional eleva-

tion showing another form of the invention; 55
Fig. 8 is a horizontal section on the line 8—8
of Fig. 7, and Fig. 9 is a detail view of the
valve ports of this form.

As illustrated in Figs. 1, 2 and 3, the
regulator comprises a body 10 provided at 60
opposite sides with valve bodies 11 and 11^a,
preferably cast upon the body 10 which, at
its lower end, is internally screw-threaded
to receive a spring-adjusting plug 12, the
purpose of which will appear more fully 65
hereinafter. The body 10 is formed with
an axial chamber 13 which, at its open end,
may be machined inwardly for a short dis-
tance to receive the lugs 14 of a diaphragm
bracket 15 which supports a diaphragm 70
chamber 16 closed by means of a removable
cover 17. The latter is provided with an
internally screw-threaded boss 18 adapted
to receive the one end of a pressure pipe 19
whereby the diaphragm chamber is con- 75
nected with the boiler in which steam is be-
ing generated. A diaphragm 20 of any cus-
tomy type is clamped between the dia-
phragm member 16 and the cover 17 and
carries a diaphragm disk 21 having a boss 80
22 which projects into an axial opening 23
formed in the diaphragm member 16. A
spring bushing 24 has its one end fixed in
the boss 22 and at its other end is provided
with an annular flange 25 resting upon one 85
end of a spring 26 which, in turn, engages
the spring-adjusting plug 12, as shown in
Fig. 1. The bushing 24 is slidably mounted
in a guide 27 which extends between and is
cast upon the lugs of the diaphragm brack- 90
et 15; the latter may be provided with lugs
15^a for the accommodation of suitable bolts
15^b whereby the diaphragm bracket is fixed
upon the body 10. The spring-bushing 24
slidably fits over a regulator rod 28 95
which projects axially through the spring-
adjusting plug 12 and has its free end
screw-threaded to receive the hand-regulat-
ing wheel 29 arranged to bear against the
lower end of the plug 12; this lower end 100
12^a is preferably of square or other angular
form to accommodate a wrench whereby the
spring plug may be screwed into the body
10. A cotter pin or the like 30 prevents
the hand wheel 29 from being unscrewed 105
from the regulator rod 28. At an interme-
diate point the spring bushing 24 is pref-
erably of increased diameter to form an an-

nular shoulder 24^a which bears against the guide 27, said bushing 24, at its enlarged section, being provided with slots 31 in which a pin 32 passing through the rod 28 is movable. A yoke 33 is slidably fitted upon the relatively enlarged section of the spring bushing 24 and is cut out as indicated at 33^a to receive the retaining spring 33^b which bears against the annular flange 25 of the spring bushing 24. At its opposite outer ends, the yoke 33 is provided with internally screw-threaded openings arranged to receive adjusting screws 34 which are maintained against rotation by means of springs 35 bearing against the milled edges of said screws 34. Valve stems 36 have their upper end portions of reduced diameter to pass through said adjusting screws 34 and form shoulders which bear 20 against the lower ends thereof, the projecting ends of said reduced end portions being fitted into recessed rings 37; the latter may be fixed upon the valve stems 36 by means of taper pins 38, which, at the same time, 25 may serve as handles for operating the valves in horizontal planes, as will appear more fully hereinafter. Spring washers 39 are located in the recesses of the rings 37 for the purpose of preventing unintentional 30 relative rotation thereof. The valve stems 36 pass through stuffing boxes 40 located upon the covers 41 which are fixed upon the valve casings 11 and 11^a, said valve stems being connected in any suitable manner 35 with the valves 42 and 42^a respectively. The latter are slidably and rotatably mounted in sleeves 43 and 43^a which are fixed in the valve casings 11 and 11^a respectively, and are surrounded by annular passages 44 and 44^a, as shown in Fig. 1. The sleeve 43, which is located in the steam line, is provided at diametrically opposite points with openings 45 of generally rectangular form, excepting that the lower left-hand corner of 40 the rectangle is not carried out, but is defined by an inclined line 46 as shown in Fig. 4. Similarly, the sleeve 43^a, which is located in the oil line, is provided with openings 45^a of generally rectangular form, excepting that the upper right-hand corner of the rectangle is not carried out, but is defined by an inclined line 46^a. These openings 45 and 45^a communicate respectively with the annular channels 44 and 44^a, and 45 also communicate with openings 47 and 47^a of rectangular form formed in the walls of the valves 42 and 42^a, it being understood that these valves are of tubular form and that the medium controlled by the valves 46 passes into the same in transverse directions and out of said valves in axial directions. With this arrangement, there is no side pressure to affect the accuracy of the operation of the valves; furthermore, if the valves are connected so that the medium

enters at *a* and leaves at *b*, in Fig. 2, only the discharge pressure of said medium will act upon the valve stem.

In the illustrated example, the valve casting 11 is located in the steam line and the valve casing 11^a is located in the oil line, so that the valves 42 and 42^a control the flow of steam and oil respectively to the burner, which may be of any customary and well known construction. The diaphragm 20 is rendered susceptible to the steam pressure in the boiler through the medium of the pipe 19, so that said diaphragm responds to variations of steam pressure in the boiler which is being heated by the burner in question. It is assumed that the boiler is under pressure and that steam from the same boiler is being used as an atomizing agent for the oil. In practice, to set and start the regulator, steam is first permitted to enter 80 the space above the diaphragm and by acting upon the same, pushes said diaphragm down and correspondingly moves the spring bushing which acts upon the pin 32 and pushes the same, with the regulator rod 28, 90 downwardly and correspondingly moves the yoke 33 which carries along the valves 42 and 42^a in a corresponding movement. This movement of the parts is continued until the boss 22 of the diaphragm disk engages 95 the guide 27 and thereby arrests the downward motion of the yoke and valves; the upward movement of these elements is arrested by the shoulder 24^a engaging the guide 27 which thus sets the limit of the valve travel 100 in both directions. When the boss 22 engages the guide 27 ports 47 and 47^a are below the ports 45 and 45^a respectively and the steam and oil valves are accordingly closed; at this stage the ports 45^a are also out of 105 vertical alignment with the ports 47^a. As the next step the spring plug 12 is screwed up and consequently, by means of the spring 26, bushing 24, spring 33^b and yoke 33, raises the valves 42 and 42^a in the sleeves 43 and 110 43^a. This is continued until the upper edges of the ports 47 rise above the lower edges of the ports 45 and steam accordingly begins to escape from the burner, after which the customary oil valve may be opened by rotating the valve 42^a in the sleeve 43^a through the medium of the handle 38 and thereby cause the ports 47^a to overlap the ports 45^a at one end and thereby permit oil to pass 115 through the regulator to the burner, after which the escaping mixture may be lighted. Should the result be a smoky flame, too much oil is probably passing to the burner, so that it is necessary, in order to obtain a clear flame, to reduce the amount thereof and to 120 increase the volume of the atomizing agent or, in the present instance, of steam. As both the steam and oil valves 42 and 42^a are assumed to be so set that the port openings 47 and 47^a overlap the ports of the sleeves 125 43 and 43^a 130

43 and 43^a to a certain extent and it is assumed that the flame is smoky, it becomes necessary to admit more steam to the burner. To do this, the adjusting screw 34 is turned 5 so that the steam valve 42 is independently raised in its sleeve 43 without being rotated horizontally therein, which adjustment gives the steam valve advanced opening with respect to the oil valve, the advantage of which 10 will be described later. Should the flame still be smoky, the oil valve 42^a should be closed somewhat by rotating the handle 38 whereby the ports 47^a are shifted slightly 15 relatively to the ports 45^a in a direction transverse to the axis of said valve, thereby reducing the effective port area through which oil may pass. After the proper setting has been secured fluctuations in steam pressure in the boilers will be reflected upon 20 the diaphragm 20 and will accordingly bring about an operation of the valves 42 and 42^a whereby the supply of steam and oil to the burner is adjusted to produce a more intense flame when the pressure drops and a 25 reduced flame when the pressure rises. With the described adjustment of the valves, the pressure gauge of the installations must be observed and the proper adjustments made by shifting the plug 12. If the pressure is 30 too high, the tension of the spring 26 should be reduced by screwing the plug 12 outwardly, the reverse operation being performed if the pressure is too low. If it is 35 desired to stop the operation of the boiler, the hand wheel 29 is screwed up against the plug 12, which causes the regulator rod 28 to descend and carry with it the yoke 33 which is connected to said rod by means of 40 the pin 32, which, during this operation, moves downwardly in the slots 31 of the bushing 34 without causing any movement of the latter. With this operation, the retaining spring 33^b is compressed, since the 45 pressure spring 26 of much heavier tension holds the spring bushing 24 in position relative to the steam pressure. As soon as the lower side of the yoke 33 engages the retaining pins 15^c, the valves are closed. If there 50 is no pressure on the diaphragm 20, the pressure spring 26 will push the spring bushing 24 up against the guide 27, in which position the valves are wide open, provided that the hand wheel 29 does not rest against the plug 12. On the other hand, when 55 maximum pressure is effective upon the diaphragm 20, the diaphragm disk 21 will be pushed down until the boss 22 engages the guide 27, in which position the valves are closed and the flame is accordingly extinguished; by means of the guide 27, the valves are protected against over-travel.

When starting the regulator by hand, it is necessary to open the same by means of the hand wheel 29, as it is of importance that steam should be admitted to the burner

first; the volume of steam may be adjusted as previously stated by screwing up on the adjusting screw 34, thereby raising the steam valve without disturbing its lateral position. This adjustment is of importance, as without 70 it, oil and steam may be started flowing at the same time, thus delaying the ignition of the mixture; if steam passes through the burner first, the smallest amount of oil passing through the oil valve will be atomized as 75 soon as it reaches said burner.

In order to illustrate the operation of the regulator, two examples are diagrammatically illustrated in Figs. 5 and 6, the first showing the steam valve partly closed, as 80 would be the case, for instance, if a light oil is being atomized, and the second showing the oil valve partly closed, as would be the case if a heavy oil is being atomized. For the purposes of description and illustration, 85 it will be assumed that at a boiler pressure of 100 lbs. both the oil and the steam valves are nearly closed, so that only the amount of oil and steam necessary to maintain this pressure passes the regulator, this condition 90 of the parts being diagrammatically illustrated at A in Figs. 5 and 6. As the steam consumption increases and the boiler pressure drops slightly, the pressure effective on the diaphragm 20 through the connection 19 95 is correspondingly reduced, so that the yoke 33, by the action of the spring 26, raises the valves 42 and 42^a in the sleeves 43 and 43^a and accordingly opens said valves, for instance, to the extent indicated at B in Figs. 5 and 6, 100 it being understood that the oil and steam valves are raised to the same extent. In this condition of the parts, the oil passes through the valve under the same constant pressure whereas the steam pressure is reduced to 95 pounds, which would not suffice, 105 ordinarily, to atomize the oil sufficiently. The steam passage or, in other words, the openings 45 in the sleeve 43 are, however, so formed that the more said openings are 110 exposed vertically, the larger becomes the area of such openings horizontally. In other words, the arrangement is such that the steam openings do not increase in the same proportion as the oil openings, but increase 115 in such a way that the proper amount of steam necessary for perfect atomization under reduced steam pressure is available at the burner. As the steam pressure continues to fall for any reason, the adjustment of the 120 valves will automatically follow the steps indicated by C, D, E and F in Figs. 5 and 6; these diagrammatic steps show that in the positions B, C and D, the steam openings increase more than the proportionate amount 125 relative to the oil openings and that from D to F the steam-opening increases are constant, whereas the free areas of the oil openings are gradually decreasing relative to the steam openings because of the form of 130

the openings 45^a, so that the proportionate reduced amount of oil which is required at the lower steam pressures will be perfectly atomized. If the oil and steam openings increased in area to the same extent at a constant oil pressure and a reduced steam pressure, the result would be a smoky flame; this possibility is entirely avoided with the present arrangement.

As shown in Fig. 3, the medium in each case, whether it be oil or steam, flows through the channels 44 and 44^a circumferentially around the sleeves 43 and 43^a, then passes inwardly through the ports thereof, and through the ports 47 and 47^a of the respective valves to the centres of such valves, which it leaves through the top and bottom and flows out at b in Fig. 2. The valves are capable of being independently adjusted in two directions, first, by moving the valves 42 and 42^a vertically in the sleeves 43 and 43^a respectively to adjust the port openings in vertical directions and by rotating said valves horizontally in said sleeves to shift the ports relatively to each other in directions transverse to the axes of the valves. The independent vertical adjustments are effected through the medium of the adjusting screws 34 while the independent horizontal adjustments are effected through the medium of the pins 38 and their correlated parts; these adjustments permit the effective areas of the openings of the individual valves to be selectively controlled and different port openings with concurrent or unified lateral motion to be created.

Another form of the invention is shown in Figs. 7 and 8, in which the valve 42^b is of the bucket type, that is, it comprises a hollow cylinder provided with rectangular ports 47^b adapted to co-operate with ports 45^b in a sleeve 43^b, which is fitted in the valve body between the inlet a' and the outlet b' thereof. Several of the ports in question are located in line, both in the valve and in the sleeve, from which it follows that only the slightest movement either up or down is required to vary the port openings whereby this form of valve is rendered very sensitive. The valve is balanced through the medium of an equalizing piston 48 which is connected with the valve by means of a hollow member 49 and is movable in a chamber 50 which may either comprise an integral part of the valve casing or be formed in a cover detachably connected therewith. The valve 42^b, member 49 and piston 48 are preferably made in one piece and the piston is preferably fitted with rings so as to form a tight fit in the chamber 50. As this valve has a passage through the member 49 from the point below the valve to a point above the piston, said valve, when operating, will be balanced and will

not be affected by any difference in pressure existing upon the two sides of the valve. It will be understood that the valve ports and the sleeve ports are constructed in substantially the same manner as described with respect to Fig. 1, and that the ports for the sleeve and the steam line are reversed with respect to the ports of the sleeve in the oil line in the same manner as previously described. It will further be understood that the valve shown in Figs. 7 and 8 is embodied in duplicate in a regulator in the same manner as illustrated in Fig. 1 and that the adjustment and operation thereof is also the same as in the form first described.

The invention provides a simple and reliable mechanism whereby the proportion of the mixture of steam and oil necessary to provide efficient and economical operation is automatically maintained at a constant point in an efficient manner and without regard to any changes which may occur in the steam pressure.

Various modifications in the specific forms shown and described may be made within the scope of the claims without departing from the spirit of my invention.

I claim:

1. An automatic regulator comprising a body having a port, a valve having a port adapted to co-operate with said first-named port to control the flow of a medium, one of said ports being of regular form and the other being of irregular form with respect thereto whereby the control of the medium is effected in a predetermined manner, and means for operating said valve.

2. An automatic regulator comprising a body having a plurality of ports, valves each having a port whereby the flow of media under pressure through said plurality of ports is controlled to produce a mixture of predetermined proportions, the plurality of ports being of irregular form with respect to their co-operating valve ports of regular form whereby the proportions in the mixture are maintained throughout the operative range of the valves and regardless of any change of pressure in one of the mediums, and means for concurrently operating said valves.

3. An automatic regulator for oil burners comprising a body having a steam port and an oil port, hollow steam and oil valves, each having a port cooperating with said steam and oil ports to control the flow of steam and oil under pressure therethrough to produce a mixture of predetermined proportions, the oil and steam passing transversely through said ports into said valves and out of the same in axial directions, the steam and oil ports being of irregular form with respect to the valve ports of regular form whereby the proportions in the mix-

ture are maintained throughout the operative range of the valves and regardless of any change of pressure in the steam, and means for concurrently operating said valves.

4. An automatic regulator for oil burners comprising a body having a pair of oppositely disposed valve casings provided with inlets and outlets, sleeves fixed in said casings and provided with ports for conducting steam and oil under pressure respectively in directions transverse to the axes of said sleeves, hollow valves slidably fitted in said sleeves and having ports co-operating with said steam and oil ports to permit steam and oil to pass into the interior of said valves and out of the same in axial directions, the valve ports being of rectangular form and the sleeve ports being of generally corresponding form but converging toward one end whereby the proportions of the mixture are maintained throughout the operative range of the valves and regardless of any change in the pressure of the steam, and means for concurrently operating said valves.
5. An automatic regulator for oil burners comprising a body having a pair of oppositely disposed valve casings provided with inlets and outlets, sleeves fixed in said casings and provided with ports for conducting steam and oil under pressure respectively in directions transverse to the axes of said sleeves, hollow valves slidably fitted in said sleeves and having ports co-operating with said steam and oil ports to permit steam and oil to pass into the interior of said valves and out of the same in axial directions, the ports being of predetermined form to maintain the proportions of the mixture substantially constant throughout the operative range of the valves and means for concurrently operating said valves.

ing co-operating ports for permitting the steam and oil to pass into the interior of said valves and out of the same in axial directions, the valve ports being of rectangular form and the sleeve ports being of generally corresponding form but converging toward one end whereby the proportions of the mixture are maintained throughout the operative range of the valves and regardless of any change in the pressure of the steam, means for concurrently operating said valves, and means for independently rotating said valves to vary the effective areas of said ports.

6. An automatic regulator for oil burners comprising a body having a pair of oppositely disposed valve casings provided with inlets and outlets, sleeves fixed in said casings and provided with ports for conducting steam and oil under pressure respectively in directions transverse to the axes of said sleeves, hollow valves slidably fitted in said sleeves and having ports co-operating with said steam and oil ports to permit steam and oil to pass into the interior of said valves and out of the same in axial directions, the ports being of predetermined form to maintain the proportions of the mixture substantially constant throughout the operative range of the valves and means for concurrently operating said valves.

In testimony whereof I have hereunto set my hand.

ERNEST GROSSENBACHER.
